BURNING TIME-FUSE.

No. 830,948.

Specification of Letters Patent.

Patented Sept. 11, 1906.

Application filed December 1, 1905. Serial No. 289,883.

To all whom it may concern:

Be it known that I, KARL WIESER, a subject of the German Emperor, and a resident of Essen-Rüttenscheid, Germany, have invented certain new and useful Improvements in Burning Time-Fuses, of which the following is a specification.

The present invention relates to burning time-fuses. It is customary to make the body of such fuses of comparatively soft metal; but it has been found that when projectiles equipped with such fuses are fired with great initial velocity the projectile bursts before the expiration of the adjusted time of burning. This is due to the fact that on firing the base of the fuse bends under the effect of its own inertia, thus creating an empty space between the base of the fuse and the priming-circle in the composition ring 15 surmounting the disk, through which space the flame of the priming-circle passes to the channel in the base leading to the detonating-chamber. The ignition of the charge is therefore not delayed till the burning out of 20 the part of the priming-circle which corresponds to the adjusted time of burning. On the contrary, the ignition of the charge takes place directly after the priming-circle has started burning.

30 The object of the present invention is to do away with the drawback above set forth.

In the accompanying drawings I have, by the way of example, shown the invention applied to a fuse which is provided with one fixed composition ring and one rotatable composition ring.

Figure 1 is a longitudinal section of the fuse and a part of the projectile, the several parts being shown in the positions which they 40 assume before firing; and Fig. 2 is a view corresponding to that shown in Fig. 1, showing how the shape of the base of the fuse is altered by firing.

The spindle A and the fuse-base B, which is 45 integral with the spindle, are made from brass, aluminium, or other metal that is easily worked. In the upper part of the spindle A, which is closed by the cap C, the nipple D and the primer-bolt E are arranged. On 50 the spindle A are placed the two composition rings F G, one of which, F, is non-rotatably connected to the spindle by a pin H. In the composition rings F G are arranged the priming-circles F' G', which are covered by felt

plates J K. In the fuse-base B is the detonating-chamber L and the channel M, leading thereto. The above-described arrangement is old.

Between the fuse-base B and the composition ring G or the packing-plate K is arranged an annular plate P, which must be made from a material that is at least as hard as the material from which the fuse-body is made and may be made from a material of greater hardness, such as steel. The plate P 65 is loosely inserted on the spindle A and lies in its entire width tightly against the felt plate K and before firing also tightly against the fuse base B. The plate P is provided with a flash-hole or vent p', registering with the priming-circle G' and with the channel M. A pin p'', which is situated in a bore in the plate P and in the base B, prevents the plate from turning relatively to the fuse-body A B when the composition ring G is adjusted or 75 when the projectile commences to rotate.

If a projectile provided with the improved fuse is fired with great initial velocity, the fuse-base B bends, as shown in Fig. 2, at the moment of firing under the inertia of the base 80 and the spindle A. The plate P does not, however, alter its shape, because its mass is small and for the further reason, if made from steel, that it possesses much power of resistance. From the foregoing it follows 85 that after firing the plate P still lies tightly against the packing-plate K, so as to prevent the premature communication of the fire from the priming-circle G' to the flash-hole p' and the channel M. The plate P thus prevents premature bursting of the projectile.

The invention may of course also be used in fuses having one composition ring only or having more than two composition rings.

Having thus described the invention, the 95 following is what is claimed as new therein:

1. In a time-burning fuse, the combination with the fuse-base having a powder-channel therein, of a composition ring having its priming-circle disposed on the side adjacent the base, and a protecting-ring formed of an incombustible material that will not become distorted on firing, and located between the composition ring and the base.

2. In a time-burning fuse, the combination 105 with the fuse-base having a powder-channel therein, of a composition ring having its priming-circle disposed on the side adjacent

the base, and means interposed between the ring and the base preventing the premature communication of the priming-circle with the powder-channel in the base when the fuse is 5 distorted under the inertia of the base.

3. In a time-burning fuse, the combination with the base having a powder-channel therein, of a composition ring having its priming-circle disposed on the side adjacent the base, and an incombustible and non-distortable protecting-ring arranged between the base and the ring.

4. In a time-burning fuse, the combination with the fuse-base having a powder-channel therein, of a composition ring having its priming-circle disposed on the side adjacent the base, an incombustible protecting-ring formed of material that will not become distorted on firing, and located between the composition ring and the base, and means for holding the protecting-ring against rotation.

5. In a time-burning fuse, the combination with the fuse-base having a powder-channel therein, of a composition ring having its priming-circle disposed on the side adjacent the base, and an incombustible protecting-ring formed of material that will not become distorted on firing, and located between the composition ring and the base, said protecting-ring being provided with a flash-hole.

6. In a time-burning fuse, the combination with the fuse-base having a powder-channel therein, of a composition ring having its priming-circle disposed on the side adjacent

the base, and an incombustible and non-distortable protecting-ring interposed between the base and the composition ring and having a flash-hole therein.

7. In a time-burning fuse, the combination with the composition ring and the fuse-base, of means interposed between the base and the ring and preventing the premature communication of the priming-circle of the composition ring with the powder-channel of the 45 base when the fuse is distorted, said means having a loose connection with the base.

8. In a time-burning fuse, the combination with the composition ring and the fuse-base, of a ring having a loose connection with the 50 base, interposed between the base and the composition ring and preventing the premature communication between the powder of the ring and the channel of the base when the fuse is distorted in firing.

9. In a time-burning fuse, the combination with the composition ring and the fuse-base, of a ring having a flash-hole, interposed between the base and the composition ring and preventing the premature communication 60 between the powder of the ring and the channel of the base when the fuse is distorted in firing.

The foregoing specification signed at Düsseldorf this 18th day of November, 1905.

KARL WIESER.
